UNITED STATES PATENT OFFICE.

WILLIAM LIVINGSTON, OF NEW YORK, N. Y., ASSIGNOR OF ONE-HALF TO WILLIAM G. DUNHAM, OF MOUNT VERNON, NEW YORK.

PIN-TAG.

1,181,903.

Specification of Letters Patent.

Patented May 2, 1916.

Application filed November 15, 1915. Serial No. 61,569.

To all whom it may concern:

Be it known that I, WILLIAM LIVINGSTON, a citizen of the United States, residing at New York, in the county of the Bronx and 5 State of New York, have invented certain new and useful Improvements in Pin-Tags; and I do declare the following to be a full, clear, and exact description of the invention, such as will enable others skilled in the 10 art to which it appertains to make and use the same.

This invention relates to improvements in tags or tickets, particularly designed for use on merchandise to receive descriptive 15 letters, numerals, or marks indicative of the quality or price of the article to which the tag is applied, and which are commonly termed "pin" tickets or tags.

The object of the invention is to provide 20 a tag of this character so constructed that when applied, it will be securely locked to the article and the pin point protected against accidental penetration of adjacent objects.

25 With this and other objects in view, the invention consists of certain novel features of construction, and the combination and arrangement of parts as will be more fully described and claimed.

30 In the accompanying drawings: Figure 1 represents a plan view of one form of the tag showing it attached; Fig. 2 is a longitudinal section taken on the line 2—2 of Fig. 1; Fig. 3 is a detail perspective view of the 35 ticket detached; Fig. 4 is a plan view of a ticket showing a slightly different arrangement of the attaching pin; Fig. 5 is a longitudinal section taken on the line 5—5 of Fig. 4; Fig. 6 is a perspective view of the ticket 40 detached; Fig. 7 is a perspective view of a ticket showing another form of applying the pin thereto; Fig. 8 is a perspective view of the pin shown in Fig. 7 detached; Fig. 9 is a plan view of another form of tag showing 45 it applied to the goods; Fig. 10 is a longitudinal section taken on the line 10—10 of Fig. 9; Fig. 11 is a perspective view showing this form of tag arranged in a strip such as is used for feeding through a 50 machine; Fig. 12 is an inverted perspective

view; and Fig. 13 is a transverse section taken on the line 13—13 of Fig. 9.

In the embodiment illustrated in Figs. 1 to 6, a ticket or tag 1 is shown which may be composed of any suitable material preferably of cardboard, and of any desired size, said ticket being provided at one edge with an inwardly extending straight walled slit 2 the walls of which are parallel and which have the appearance of a single line 55 owing to the fact that the walls thereof normally contact and thereby prevent the free ends of said walls from engaging adjacent objects, such as would be liable to tear off one of said walls and release the ticket. 60 This ticket 1 is designed for containing indicating marks according to the use for which it is designed.

In the form shown in Figs. 1 to 3, a pin 3 has one end extended through the ticket 1 70 and bent toward the slit edge of the ticket and disposed flat against the face of the ticket on the side opposite that which is engaged by the body portion of the pin. This bent ticket penetrating end 4 may be of 75 any desired length, and when applied, is arranged substantially parallel with the body portion thereof. The pointed end 5 of the pin projects beyond the slit edge of the ticket 1 a sufficient distance to adapt it 80 to be bent inwardly and clamped against the face of the ticket on the side opposite that which carries the body portion of the pin. This pointed end 5 is of a length sufficient to adapt it to be inserted in the slit 2 and 85 bent with the bent portion thereof interlockingly engaging said slit, whereby the pin and ticket are held in locked engagement against lateral movement by the straight parallel walls of the slit, the pointed end of the pin being extended inwardly and disposed flat against the face of the ticket adjacent the terminal of the bent end 4 of the pin.

90 From the above description, it will be 95 obvious that in the use of this ticket formed as described, the pointed end of the pin is inserted through the goods or article to which it is to be attached and then said end is bent inwardly through the slit 2 with 100

its point arranged as above described, whereby an article engaging loop 6 is formed on the rear face of the ticket which securely connects the ticket to the goods.

5 In the form shown in Figs. 4 to 6, the pin 3' has one end 4' extended through the ticket 1 and bent flat against the opposed face thereof. The pin is then again inserted through the ticket at a point 7, forming a 10 clamping loop 8 on the side of the ticket opposite to that on which the end 4' is disposed. This pin, at its second point of passage through the ticket is offset as shown at 9, and the body portion thereof extended 15 toward the slit edge of the ticket with its pointed end projecting beyond said edge, similar to the device above described and shown in Figs. 1 to 3. The pointed end of this pin 3' is then bent inwardly through 20 the slit 2 in the ticket, with its terminal disposed adjacent to the offset portion 9 thereof. This, it is of course understood, is done after the pin has been passed through the article to which the ticket is to be attached, 25 the loop formed between the bent portion of the pin and the offset portion 9 thereof being designed to connect the ticket to the article.

30 In the form shown in Figs. 7 and 8, the ticket 1 is the same as that shown in the other figures, but the pin 10 is shown differently connected therewith. This pin 10 is shown T-shaped with the head formed by bending one end of the pin into an elongated loop 11, the side member 12 of which is engaged with one face of the ticket 1, and the ends thereof extending through the ticket, thereby positioning the other side member 13 of the loop on the opposed face 40 of the ticket. This loop-shaped head is formed by bending the wire from which the pin is constructed laterally at right angles to the pin, then inwardly in a plane parallel with the right angular portion and extending 45 it beyond the opposite side of the pin, and then bending its terminal inwardly and positioning it adjacent to and in alinement with the right angular portion. The shank or pin body 14 extends centrally from the side member 13 of the loop 11 at right angles thereto and extends toward the slit edge of the ticket with the point thereof projecting beyond said edge and adapted to be bent backward through the slit 2 after it 50 has been passed through the article to which the ticket is to be attached. When the point is so bent it is disposed adjacent the side member 12 of the loop 11 and is protected thereby against accidental engagement with adjacent objects.

55 From the above description, it will be seen that this ticket, while simple in construction, may be reliably connected and locked to the article to which it is to be applied, by

means of the interlocking engagement of the 65 pin with the slit 2 of the ticket.

In the form shown in Figs. 9 to 13, the tickets 15 are shown connected in the form of a strip designed to be fed through a machine for printing symbols or price marks 70 thereon. Each of these tickets 15 is constructed exactly the same as those shown in the other figures except that at the inner end of the slit 2' which is formed in one end thereof and the walls of which normally 75 contact, is an aperture 16, here shown round, although obviously it may be of any other desired shape. This aperture 16 is designed to perform the double function of a lock for 80 the pin and as a guide for the feeding mechanism when the strip is fed through a printing machine. After the pin is inserted through the slit and bent into engagement with the ticket at the side of the aperture 16 opposite the slit 2', the walls of this slit will 85 return to contacting closed position and prevent all possibility of the ticket slipping off the merchandise or of the goods being pulled around over the pin, or of the walls of the slit being engaged with surround- 90 ing objects.

In the use of the tickets shown in Figs. 9 to 13, it is of course understood that the tickets are separated individually from the strip and the pin 10 thereof which is exactly 95 like the pin 10 shown in Figs. 7 and 8, is passed through the material of the article to which the tag is to be applied, and said pin is then bent inwardly through the slit 2' across the aperture 16, and into engagement 100 with the outer face of the tag, as is shown clearly in Fig. 9, the bent portion of said pin engaging the inner wall of the opening, and by means of which the pin is held 105 against lateral movement.

I claim as my invention:

1. A pin tag comprising a ticket having a pin fixed at one end thereto with its point projecting beyond one edge of the tag, said edge having a slit formed therein and disposed under said pin to adapt the point thereof to enter therethrough when bent inwardly, the outer ends of the walls of said slit being parallel and normally contacting to provide a smooth unindented edge 115 through which said slit extends to prevent engagement of the walls of said slit with adjacent objects.

2. A pin tag comprising a ticket having a slit extending inwardly from one edge thereof, a T-shaped pin formed from a single piece of wire, the head thereof being engaged with said ticket and extending in a plane at right angles to said slit, said head comprising alined loops extending laterally 120 at right angles on opposite sides of the pin shank, the side members of one loop being 125 in longitudinal alinement with those of the

other and spaced apart a distance substantially equal to the thickness of the ticket to be clamped between them, and one side member of each loop arranged on one face of said ticket and the other on the opposite face thereof, the shank of said pin being arranged in alinement with said slit.

In testimony whereof I have hereunto set my hand in presence of two subscribing witnesses.

WILLIAM LIVINGSTON.
